UNITED STATES PATENT OFFICE

165,966

FLIGHT TRAINER HOOD

Frederic W. Davis, Caldwell, N. J., assignor to
Curtiss-Wright Corporation, a corporation of
Delaware

Application May 25, 1951, Serial No. 15,317

Term of patent 7 years

(Cl. D71—1)

To all whom it may concern:

Be it known that I, Frederic W. Davis, a citizen of the United States of America and residing in the city of Caldwell, county of Essex, and State of New Jersey, have invented a new, original, and ornamental Design for a Flight Trainer Hood, of which the following is a specification, reference being had to the accompanying drawings, forming a part thereof.

In the drawings:

Fig. 1 is an elevational view in perspective of a flight trainer hood showing my new design looking from the front toward the rear along the left side;

Fig. 2 is a similar view looking from the rear toward the front along the left side;

Fig. 3 is a similar view looking from the front toward the rear along the right side, and

Fig. 4 is a plan view from above.

The characteristic features of my design reside in the hood configuration, as distinguished from the supporting base and the recessed recording unit, as shown in the drawings.

I claim:

The ornamental design for a flight trainer hood, substantially as shown and described.

FREDERIC W. DAVIS.
